ADJUSTABLE HEADWEAR

Benjamin Rosset, Brooklyn, N. Y.

Application May 8, 1956, Serial No. 583,544

1 Claim. (Cl. 2—197)

The present invention relates generally to improvements in headwear, and in particular it relates to improved caps and hats which are adjustable in size.

Hats, caps and other types of headwear are available in innumerable shapes, styles and colors, as well as in a large range of sizes. Inasmuch as the stock and inventory of a retailer or distributor of headwear is of necessity limited by the available space or available capital, he must confine his stock to a small number of most popular styles and colors and usual head sizes. However, were the headwear of adjustable size, so as to eliminate the need for carrying the various individual sizes, the variety of styles and colors which may be carried can be greatly increased. There have been many proposed headwear constructions for permitting the adjustment in their size but these possessed many drawbacks and disadvantages. They have generally been characterized by their complexity, unattractive appearance, limited adjustability and discomfort accompanying their use.

It is thus a principal object of the present invention to provide an improved headwear.

Another object of the present invention is to provide an improved article of headwear such as a hat or cap which is adjustable in size.

Still another object of the present invention is to provide an improved article of adjustable headwear of simple and inexpensive construction.

A further object of the present invention is to provide an improved article of headwear of adjustable size characterized by its simplicity in operation and attractive appearance.

The above and other objects of the present invention will become apparent from a reading of the following description, taken in conjunction with the accompanying drawing, wherein

Figure 1 is a top perspective view of a preferred embodiment of the present invention in the form of a cap;

Figure 2 is a horizontal sectional view, taken through the crown of the cap with the visor portion partially broken away;

Figure 3 is a sectional view, taken along line 3—3 in Figure 2;

Figure 4 is a perspective view of another embodiment of the present invention in the form of a cap;

Figure 5 is a horizontal sectional view, taken along the crown of the cap, the visor being partially broken away;

Figure 6 is a sectional view, taken along line 6—6 in Figure 5; and

Figure 7 is a perspective view of still another embodiment of the present invention in the form of a hat; and

Figure 8 is a section on the line 8—8 of Figure 6.

In a sense, the present invention contemplates the provision of an improved article of headwear of adjustable size, comprising a crown portion having a lower opening formed therein which is surrounded by a head band defining the lower border of said crown portion, a plurality of circumferentially spaced loops disposed along

2

the outer face of said head band, a circumferentially extending strap surrounding said head band and registering with said loops, and means for adjusting the circumference of said strap. The invention may be applied to caps, hats or the like as will be hereinafter set forth.

Referring now to Figures 1 to 3 of the drawings which illustrate a preferred embodiment of the present invention, the numeral 10 generally designates the improved cap which includes a crown portion 12 having a lower peripheral rim defining a head band portion 14 which is formed integral with the crown 12. The crown 12 may be formed in any conventional manner and includes a pair of interfitting top and skirt panels 16 and 18 which are suitably interstitched along their abutting edges, the top panel 16 and the skirt panel 18 extending forwardly and overlapping the upper face of a visor 20 which projects forwardly from the under edge of the head band 14.

The crown top and skirt panels 16 and 18 may be formed of any suitable material such as fabric, plastic, leather or the like, and the visor 20 may be faced with a material similar to that forming the crown or of any other desirable material. The inner face of the crown 12 is provided with a lining 22 which may completely coincide with said inner face or may cover only a part thereof, the lower edge of the lining 22 being inwardly hemmed as at 24 and being embraced by the lower border of the head band 14 which is likewise folded inwardly as at 26. A sweat band 28 is located within the crown 12 along the inner face of the head band 14.

Located along the outer face of the head band 14 are a plurality of circumferentially spaced loops 30 which may be formed of the same material as the crown 12 or of any other desirable material of the same or contrasting colors. The upper ends of the loops 30 are secured to the crown 12 by means of stitches 32 and the lower edges of the loops 30 are secured to the crown by means of stitches 34 which pass through the loops 30, the hemmed edges of the crown 12 and the lining 22 and the lower edge of the sweat band 28.

40 A belt or strap 36 surrounds the head band 14 and passes through the loops 30, the forward portion of belt 36 being disposed between the visor 20 and the overlying portion of the crown 12. It should be noted that the forward portion of the crown 12 is separably secured to the upper face of the visor 20 by means of snap fasteners in the conventional manner. One of the ends of the belt 36 carries a buckle 38 and the other end thereof is provided with a tongue 40 having formed therein longitudinally spaced holes 42 which are selectively engaged by the buckle 38 thereby to permit adjustment in the length and hence the circumference of the belt 36.

The adjustability in size of the aforesaid cap is apparent from the above description. The cap is merely donned by the wearer and its circumference adjusted by 55 adjusting the length or circumference of the belt 36 by means of the buckle 38 engaging a selected opening 42. It is important to note that the head band 14 is characterized by the absence of any elastic material which would contribute to an uncomfortable article of headwear.

60 The embodiment of the invention illustrated in Figures 4 through 6 of the drawings differ from that above described principally in the location and construction of the loops and in the disposition of the adjusting belt. The cap is provided with a crown portion 52, visor 54 and head band 56 as previously described. Disposed along the inner face of the crown 52 is a lining 58, the lower edge of which is hemmed and embraced by the hemmed lower edge of the crown 52. A sweat band 60 is located along the inner periphery of the head band 56. Stitching 65 is provided to secure sweat band 60 to the lower folded edges of lining 58 and crown 52. Located along the outer face of the head band 56 at the

sides, the rear and points intermediate the sides and rear are a plurality of loops 64, the upper and lower edges of which are secured to the cap or hat by means of decorative studs 66, 68 which are provided with a rearwardly projecting pair of pointed soft metal fingers 67. In assembly, the fingers 67 of the studs 66 are passed through the loop and through the material forming the crown 52 and are then spread outwardly. The lining 58 covers the fingers 67.

A belt 70 passes through the loops 64, the ends of the belt 70 adjustably engaging one another by means of a buckle 72 carried by one end of the belt 70, the other end of the belt 70 having a series of holes to permit the adjustability of the belt 70.

The adjustment of the sizes of the cap last described is similar to that of the first embodiment differing only in that the end portion of the crown is detached from the visor 54 during the adjustment operation and is thereafter re-secured.

In Figure 7, there is illustrated a felt hat of conventional construction embodying the present invention. The hat includes a crown portion 74 having a lower head band 76 and provided with a brim 78. A plurality of loops 80 are secured to the outer face of the head band 76 by means of decorative studs 82, as previously described. A belt 84 of adjustable length engages the loops 80. The adjustability and length of the loops 80 may be achieved by means of a buckle or any other suitable device. The adjustment in size of the hat illustrated in Figure 7 is similar to that of the caps previously described.

While there have been described and illustrated preferred embodiments of the present invention, it is apparent that numerous alterations and omissions may be made without departing from the spirit thereof.

I claim:

An improved article of headwear of adjustable size comprising a crown portion having a lower opening formed therein which is surrounded by a head band defining the lower border of said crown portion, a visor secured to and projecting outwardly of said head band, said crown portion overlying the upper face of said visor, a plurality of circumferentially spaced vertical loops disposed along the outer face of said head band, the upper and lower ends of said loops being secured to said head band by means of studs engaging said upper and lower ends, said studs being provided with enlarged decorative heads and rearwardly directed legs passing through said loops and said crown portion and being laterally bent, a liner disposed within said crown portion and overlying said stud legs, a circumferentially extending belt completely encircling said head band and registering with said loops, the forward portion of said belt being concealed between said visor and the overlying portion of said crown, and buckle means carried solely by said belt for adjusting the circumference of said belt and maintaining said belt in adjusted position.
